GARMENT HANGER

Frank P. Mies, Chicago, Ill.

Application February 19, 1938, Serial No. 191,544

3 Claims. (Cl. 223—93)

This invention relates to a garment hanger and more particularly to a hanger with a device for fastening clothes thereon.

One feature of this invention is that the garments are securely retained in position without danger of slipping or falling; another feature is that the fastening device does not interfere with the removal or replacement of garments; another feature is that when the fastening device is removed from engagement with the garments it may be locked in such position; still another feature of this invention is that the fastening device remains in contact with the garment without movement thereon; yet another feature of this invention is that the contact holding the garment is of such a nature as to prevent tearing or even creasing thereof; still another feature is the production of a device of this character of sturdy construction with simplicity of operation; other features and advantages will be apparent from the following specification and drawing, in which—

Fig. 1 is a front elevational view of an embodiment of my invention; Fig. 2 is a plan view; Fig. 3 is a fragmentary vertical sectional view; Fig. 4 is a fragmentary front elevational view with the outer casing and a portion of the inner casing broken away; and Fig. 5 is a fragmentary view along the line 5 of Fig. 3.

Ordinary garment hangers frequently allow garments to slip or fall from the hanger. As a result, many devices have been developed to insure retention of garments in place on the hanger. Many of these devices tend to damage clothes, tearing or creasing them at the point of contact. Others are too complicated in their mechanical design and are difficult to use. Still others are not of a sufficiently simple and sturdy construction to withstand hard usage.

My invention obviates these and other difficulties. My invention contemplates a resilient rod in yielding releasable engagement with a garment carried by a horizontal bar.

In the embodiment of my invention disclosed herein a substantially horizontal bar 10, of the usual garment hanger type, carries a hook 11, or other means of support. A rod 12, preferably composed of steel or other resilient material, is movably mounted on the inner casing 13 or other similar means carried by the horizontal bar or hook. When the type of mounting described herein is used the rod should have a cross-section shape other than circular and preferably is a flat strip rectangular in cross-section.

The ends of said rod, projecting from the cas-

ing, serve as arms for yieldingly gripping a garment on the horizontal bar. The rod is preferably slightly arcuate in shape in order that the actual contact with the garment may be made only at the extreme ends of the rod. To the ends 5 of the rod 10 may be fastened small buttons, 14 and 15, made of wood or other suitable material. Small pads, 16 and 17, of felt, rubber, or similar material, may, if desired, be sunk in the horizontal bar at the points of contact with said 10 buttons.

The shank 18 of the hook 11 passes through the horizontal bar 10 and is secured thereto by a rivet, or nut 19. Around said shank is the inner casing 13. Said casing may be secured at 18 its base to the horizontal bar 10, preferably by small projecting teeth 20 driven thereinto, and at its upper end to the shank 18 of the hook by a cap 21.

The inner casing 13 is provided with two vertical slots 22 and 23 on opposite sides thereof, said slots being in alignment with the horizontal bar 10. The ends of the rod 12 project from the slots 22 and 23 and are retained in alignment with the horizontal bar thereby. Said slots extend from a point near the base of the inner casing to the horizontal slots 24 and 25.

The rod 12 is vertically slidable in the slots 22 and 23 and horizontally rotatable in the slots 24 and 25 when raised thereto. A spring 26 urges 30 the rod 12 in the slots 22 and 23 into yielding engagement with the horizontal bar 10 or a garment carried thereby, whenever said rod is in alignment with the horizontal bar.

The rod 12 may be pivotally and slidably mounted on the shank 18 of the hook 11 or on the casing 13. Or, if desired, an outer casing 27 may be slidably and rotatably fitted over the inner casing 13. Said outer casing is provided with openings 28 and 29 on opposite sides thereof, said openings being of the same shape (rectangular in this instance) as the cross-section of the rod 12 which projects from said openings. The casing 27 with the openings 28 and 29 closely fitted to the rod 12 thus serves to hold said rod in position and to prevent rotation about the axis of the rod.

The rod 12 may be bent in the middle thereof in order to pass around the shank 18 of said hook, as shown in Fig. 5. Thus, the shank of the hook together with the casings 13 and 27 serves as a mounting for said rod, retaining it in position.

To place a garment on the hanger the rod 12 is raised in the vertical slots until the transverse 55

openings or horizontal slots 24 and 25 are reached. At this point, the rod may be rotated in either direction as shown in Fig. 2. The outer casing 27, of course, moves with the rod. The 5 horizontal slots serve to lock the rod 12 in the elevated position, and the garment is placed on the hanger. When the rod 12 is swung back into alignment with the vertical slots the spring 10 26 urges it into yielding engagement with the garment which it securely retains in place. The buttons 14 and 15 and the pads 16 and 17 aid in preventing any injury to the garment.

This application is a continuation-in-part of my copending application Serial No. 170,689, filed 15 October 23, 1937.

The foregoing detailed description has been given for clearness of understanding only, and no unnecessary limitations should be understood therefrom, but the appended claims should be construed as broadly as permissible in view of the prior art.

I claim:

1. A garment hanger of the character described for yieldingly gripping a garment thereon including: a horizontal bar adapted to carry said garment; a vertically slotted inner casing mounted on said bar; a resilient rod pivotally mounted in said casing with the ends thereof extending through said slots in alignment with said bar, said rod being vertically slidable in said slots; at least one transverse opening in said casing communicating with the upper end of each of said slots, said opening being adapted to permit horizontal rotation of said rod, and to retain said rod in an elevated position when out of alignment with said bar; an outer casing slidably and rotatably mounted on said inner casing, having therein openings through which said rod passes; a pair of smooth buttons mounted on the ends of said rod adapted to engage said garment; spring

means adapted to urge said buttons into yielding engagement with a garment carried by said bar when the rod is in alignment with the bar; and a hook adapted to support said bar.

2. A garment hanger of the character described for yieldingly gripping a garment thereon including: a horizontal bar adapted to carry said garment; a vertically slotted casing mounted on said bar; a substantially horizontal rod pivotally mounted in said casing with the ends thereof extending through said slots in alignment with said bar, said rod being vertically slidable in said slots; and at least one horizontal slot in said casing communicating with each of said slots, said horizontal slot being adapted to permit horizontal rotation of said rod, and to retain said rod in an elevated position when out of alignment with said bar.

3. A garment hanger of the character described for yieldingly gripping a garment thereon including: a horizontal bar adapted to carry said garment; a casing mounted on said bar, said casing being provided with a pair of vertical slots in alignment with said bar; a resilient rod pivotally mounted in said casing with the ends thereof extending through said slots in alignment with said bar, said rod being vertically slidable in said slots; a pair of horizontal slots in said casing, each of said horizontal slots communicating with the upper end of one of said vertical slots, said horizontal slots being adapted to permit horizontal rotation of said rod, and to retain said rod in an elevated position when out of alignment with said bar; spring means for urging said rod into yielding engagement with a garment carried by said bar when said rod is in said vertical slots and in alignment with said bar; and a hook adapted to support said bar.
